UNITED STATES PATENT OFFICE.

EDGAR E. BROSIUS, OF PITTSBURGH, PENNSYLVANIA.

FURNACE-TAPPING MACHINE.

Application filed November 26, 1924. Serial No. 752,361.

The present invention relates broadly to drilling apparatus, and more particularly to apparatus of this character adapted to be used for the tapping of blast furnaces or the raveling of tapping holes which have become clogged while the iron is flowing.

It has heretofore been proposed in the art to which the present invention relates to provide tapping apparatus mounted to be moved 10 toward and away from the tapping hole in the general line thereof, and also apparatus adapted to be swung toward and from the tapping hole, both in a horizontal and vertical direction. With all such means, however, the 15 mounting has not been such as to cause the same to move to an inoperative position wholly out of the way, or of such construction as to adapt the same for use in raveling a tapping hole clogged with coke or other materials while the iron is flowing.

The tapping out operation is exceedingly dangerous, and the intense heat makes the operation exceedingly uncomfortable. Due to the inefficiency of existing machines generally, it is still quite common practice to tap by hand. It is one of the objects of the present invention to provide an easily operated tapping machine capable of being entirely controlled and held in operative position, or 20 moved to an out of the way inoperative position, by an operator located well away from the danger zone of the tapping hole.

A further object of the invention is to provide an apparatus of the character referred to capable of being moved into, and clamped in, operative relation to a tapping hole or over a skimming trough to permit raveling of the tapping hole where such operation becomes necessary.

40 In the accompanying drawings there is shown, for purposes of illustration only, the preferred embodiment of the present invention, it being understood that the drawings do not define the limits of the invention, as changes in the construction and operation 45 therein disclosed may be made without departing either from the spirit of the invention or the scope of my broader claims.

In the drawings:—

50 Figure 1 is a sectional elevation, largely

diagrammatic, showing one form of apparatus embodying the present invention;

Figure 2 is an end elevation of the tapping apparatus shown in Figure 1;

Figure 3 is a longitudinal sectional view, 55 on an enlarged scale, with certain of the parts shown in elevation, through the tapping apparatus shown in Figures 1 and 2, and

Figure 4 is a detail sectional view, on a still larger scale, of a portion of the operating 60 mechanism shown in Figure 3.

In the accompanying drawings there is illustrated a portion of a blast furnace wall 2 with a bustle pipe 3 in cooperative relation thereto, there being the usual shaft 4 for clamping the mud gun or tapping apparatus in operative relation to the furnace. All of these features of construction may be in accordance with standard practice, and may be varied as required by the particular furnace design.

The tapping apparatus is adapted to be suspended from the bustle pipe 3 in such manner that it may be swung into substantially horizontal operative position, or to substantially vertical inoperative position wholly out of the way of operators engaged about the furnace. In order to permit such a mounting, the frame 5 of the tapping machine is prefer-

ably formed, adjacent the opposite ends thereof, with spaced upwardly extending supporting lugs 6, to each of which is pivotally connected a link 7 having a plurality of longitudinally spaced perforations 8 in the upper end thereof.

These links and the openings 8 are adapted to adjustably co-operate with other links 9 having similar openings 10 in their lower ends, and pivotally connected at their upper ends to a bracket 11 secured in any desired manner to the bustle pipe, as, for example, by straps 12. Preferably the front

set of links 9 will be curved, as clearly shown in Figure 1, the curvature being substantially the same as the curvature of the bustle pipe to more easily permit the tapping machine to be swung to inoperative position, as will be hereinafter fully apparent. The links 7 and 9 for the front of the tapping machine

also preferably carry a protecting sheathing 13 formed in sections to permit the relative 100

adjustment of the links as required, one of the sections carrying an overlapping or projecting strip 14 for closing the joint therebetween.

Also carried by the lugs 6, adjacent the front of the machine, is a clamping arm 15 having a recess 16 at its outer end adapted to embrace the mud gun shaft 4 for holding the tapping machine in predetermined spaced operative relation to the furnace. This clamping arm has a downwardly extending projecting lug 17 of such length that it is adapted to engage one side of the shaft 4 as the machine is swung into operative position to limit further movement thereof toward the furnace and properly center the arm so that the recess 16 will engage the shaft. This arm is bifurcated adjacent the lug 6 to permit the same to be attached thereto, and each of the forks has pivotally connected thereto a curved arm 18, which arms extend upwardly in diverging relationship and are pivotally connected at their upper ends to lifting rods 19. The pivotal connecting means between the diverging arms 18 and the lifting rods preferably comprises a continuous pin 20 having an elongated anti-friction roller 21 surrounding the same. The lifting rods are in turn connected by cables 22 to a cross-head 23, to which is connected a single lifting cable 24 passing over a pulley 25 to a fixed pulley 26 on a support or wall 27 at a considerable distance from the blast furnace. The lifting cable passes over the pulley 26, thence around a pulley 28, and returns to the bracket 29 for the pulley 26, on which it is dead ended. The pulley 28 is carried by the upper end of a piston rod 30, and is adapted to be raised and lowered in known manner by a fluid pressure cylinder 31. By directing fluid into the cylinder 31 in such manner as to move the pulley 28 downwardly, the apparatus will be swung from its full line position of Figure 1 to its dotted line position, while by permitting the pulley 28 to move in the opposite direction, the apparatus will again be lowered to its operative position.

It is desirable that the construction of the apparatus be such that the clamping arm shall be first automatically released from the shaft 4 before commencement of the lifting operation for the apparatus itself. This is accomplished by connecting the lifting rods 19 and the arms 18 directly to the clamping arm, thereby insuring initial movement of the clamping arm from its full line position of Figure 1 to its dotted line position. When this dotted line position has been reached, the roller 21 will engage the protecting sheathing 13 on the front arms and tend to raise the entire apparatus. The movement of the roller 21 with respect to this sheathing is limited by angles 32 and 33 extending transversely thereof. At the commencement of the upward movement of the apparatus the roller 21 will be in engagement with the angle 32.

Thereafter, after the front links 7 have passed a substantially horizontal position, the roller will move into engagement with the other angle 33 and remain in this position throughout the rest of the lifting operation, the pivotal connection between the lifting rods 19 and the arms 18 permitting the clamping arm 15 to move upwardly into the dotted line position shown in Figure 1, wherein it is entirely out of the way.

The broad features of suspending a tapping apparatus by the use of spaced pairs of links, as shown herein, is claimed in my United States Patent No. 1,534,838 of April 21, 1925, and over which the present application constitutes an improvement.

Due to the intense heat to which the parts of the tapping apparatus are subjected when in use, either for the initial tapping out of the opening or for the subsequent raveling thereof when the iron is flowing, it is necessary that the parts thereof be positioned with respect to their ability to withstand temperature, and that the structure be made such as to accommodate this arrangement. For this reason, the frame 5 carries at its rear portion a driving motor 34, this motor being the most susceptible to temperature conditions. In front of the motor is a drill feed cylinder 35, and projecting from the drill feed cylinder, at the end opposite the motor 34, is a drill bar 36. Substantially this same general arrangement of elements is disclosed in patent to Judy No. 1,424,483, dated August 1, 1922, and as claimed in his reissue Patent No. 15,928 of October 7, 1924. The present application, however, embodies improvements over the Judy patent which have been found desirable from the standpoint of increased efficiency of operation.

In accordance with the preferred embodiment of the invention, the drill feed cylinder 35 is detachably connected at one end to a main casting 37 carrying the rear lugs 6 to which the links 7 are connected. At its opposite end the cylinder is connected to a head 38. Both the main casting 37 and the head 38 are carried within the protective casing or frame 5 before referred to, this frame at one end carrying a casting 39 on which are formed the lugs 6 for the front links 7. The space between the frame 5 and the drill feed cylinder is preferably filled with a suitable heat insulating material 40, such as asbestos, serving to protect the cylinder from the intense heat to which it is subjected, particularly when raveling out a tapping hole while iron is flowing through the skimming trough.

Mounted within the drill feed cylinder is a drill feed piston 41 having suitable packing means 42 between the periphery of the same and the inner wall of the cylinder. This piston has an intermediate inwardly extending flange 43, and has oppositely extending

threaded portions 44 on opposite sides thereof. The flange 43 is adapted to cooperate with packing washers 45 held in position by clamping rings 46 engaging the threaded portions 44. The piston is carried by anti-friction bearings 47, preferably in the form of roller bearings mounted on a sleeve 48 having an intermediate shoulder 49 and threaded ends 50 and 51. After the parts have been assembled 10 on the sleeve 48, a lock nut 52 is screwed on to the threaded end 50. Thereafter, a coupling sleeve 53 is threaded on to the portion 51 and the drill feed piston rod 54, preferably of tubular construction, is threaded into the 15 coupling sleeve. These parts, either before or after the complete assembly thereof, may be inserted within the drill feed cylinder, and the head 38 applied and fixed in position by screws 55 extending through the main frame 20 5. Thereafter, the packing and packing gland 56 may be added to prevent leakage around the drill feed piston rod. A drill bar coupling 57 may then be threaded on to the outer end of the drill feed piston rod for the 25 reception of the drill bar 36.

It is necessary during the operation of the apparatus to impart both a longitudinal and a rotary motion to the drill bar. The longitudinal motion may be imparted by means of 30 the piston 41, the drill feed cylinder 40 having a fluid pressure connection 58 with one end thereof, and a second connection 59 with the opposite end, whereby fluid may be directed at will into the drill feed cylinder for 35 effecting the desired longitudinal movement of the drill bar. Rotary movement is imparted to the drill bar by the motor 34 and the drill shaft 60 in alignment with the motor shaft 61. The drill shaft 60 is secured in 40 position within a collar 62 by a suitable transversely extending key 63, thereby preventing longitudinal movement of the drill shaft with the drill feed piston rod 54. This drill shaft, however, is of angular cross section as clearly 45 shown in Figure 4, and the sleeve 48 is provided with a correspondingly shaped bore whereby the drill shaft will impart rotation to the sleeve and thence to the drill feed piston rod, while permitting the piston 41 to 50 remain non-rotatably within its cylinder by reason of the anti-friction bearings 47 between the sleeve and piston. The end 61 of the motor shaft may also be square to impart rotation to the collar 62. This collar is rotatably 55 mounted within the casing 37 by anti-friction bearings 64, which bearings also serve as thrust bearings for the flange 63 on one end of the collar, and the nut 66 on the opposite end thereof. The space intermediate the 60 bearings 64 may be constructed to provide packings 67 similar to the packings 45 before described. These bearings may also be protected by a cover plate 68 secured to the casting 37.

65 Mounted above the drill feed cylinder is a

blower cylinder 69 having a blower pipe 70 movable longitudinally therethrough for blowing out foreign material from the tapping hole during the tapping operation. The blower pipe may be advanced and retracted 70 by a piston 71 secured thereto, the piston being moved in one direction by air supplied through the connection 72 and in the opposite direction by air supplied through the connection 73. The blower cylinder, at its end adjacent the front lugs 6, may be provided with similar lugs 6' adapted to receive the connecting pin which pivotally connects the links 7 to the lugs 6. At its opposite end the blower cylinder may be supported by a pin 74 extending 75 through a suitable projection 75 on the rear lugs 6 and held in position by a nut 76.

At certain times during the operation of the tapping apparatus it may be desirable to supply oxygen through the blower pipe for the 80 purpose of burning out scull. This may be accomplished by extending a fluid delivery pipe 77 centrally through the piston 71 and the blower pipe adapted to deliver either air or oxygen to the blower pipe at 85 its end adjacent the drill bar. At its opposite end the pipe 77 may have an air supply connection 78 and an oxygen supply connection 79, these connections being adapted to be controlled at will by suitable valves 80. The oxygen may be supplied from a tank 81 preferably carried by the drilling apparatus so as to be swung into and out of operative position therewith, and conveniently mounted on the cover plate 82 for the 90 motor 34. It will be apparent that each of the connections 58, 59, 72, 73, 78 and 79 may have a flexible portion therein so as not to interfere with the swinging of the apparatus from one position to the other, such flexible 95 connections preferably comprising metallic sections adapted to withstand the temperature conditions to which the apparatus is subjected.

In operation, when it is desired to tap a 100 hole for the iron, the entire apparatus will be lowered from its dotted line position of Figure 1 to its full line position, the lowering operation bringing the projections 17 on the clamping arm into engagement with the shaft 4 for properly centering the parts. Thereafter, further slackening the cable 24 will cause the clamping arm to move to the desired position. At this time the motor 34 may be energized for rotating the drill bar, and fluid may 105 be supplied through the connection 58 for moving the drill feed piston rod to advance the drill bar, and through the connection 72 for maintaining the blower pipe in the desired operative position. At the completion 110 of the tapping out operation, the fluid will be supplied through the connections 59 and 73 for returning the drill bar and the blower pipe respectively. Thereafter, should it be 115 necessary to ravel the tapping hole, the en-

closing casing or frame 5, together with the heat insulating material 40, and the location of the motor 34, permit the apparatus to be lowered into position over the skimming trough without injury thereto. The automatic operation of the clamping arm also makes it unnecessary for an operator to occupy any dangerous position adjacent the tapping hole.

10 The advantages of the present invention arise from the provision of a tapping machine adapted to be moved into and out of operative position and automatically held in the inoperative position when moved thereto.

15 Further advantages of the invention arise from the provision of a construction capable of effectively withstanding high temperatures and operable for supplying either air or oxygen to the blower pipe as desired.

20 I claim:

1. Blast furnace tapping apparatus, comprising a drill, spaced links forming a suspension for the drill and causing the same to move to an overhead position through a predetermined path, means for holding the drill temporarily in operative relationship to the tapping out hole of a blast furnace, and means operable before movement of the drill into or out of operative position for bringing said means into or out of operative holding position, substantially as described.

2. Blast furnace tapping apparatus, comprising a bustle pipe, suspension means pivotally connected at spaced points to said pipe, a drill pivotally connected to said suspension means, means for swinging the drill into and out of operative position with respect to the furnace, certain of said suspension means being curved to substantially conform to the curvature of the bustle pipe, and a shield carried by said curved suspension means, substantially as described.

3. Blast furnace tapping apparatus, comprising a rotatable drill, suspension means therefor comprising a plurality of links pivotally connected adjacent the end and arranged to permit the drill to be swung into substantially horizontal tapping position or into substantially vertical inoperative position, means carried by said apparatus remote from the drill and entirely rearwardly of said links for imparting continuous rotation thereto with the drill in any position, and means for protecting said last-mentioned means from the heat of the furnace being tapped, substantially as described.

4. Blast furnace tapping apparatus, comprising a rotatable drill, suspension means therefor comprising a plurality of links pivotally connected adjacent their ends and arranged to permit the drill to be swung into substantially horizontal tapping position or into substantially vertical inoperative position, means carried by said apparatus remote from the drill for imparting rotation thereto

while the drill is held against longitudinal movement, and means intermediate the drill and said rotating means for advancing or retracting the drill irrespective of whether the drill is rotating or not, substantially as described.

5. Blast furnace tapping apparatus, comprising a bustle pipe, a drill, suspension means therefor arranged to permit the drill to be swung into and out of tapping position, said suspension means comprising spaced links pivoted at their lower ends to spaced points on the drill and at their upper ends to spaced points on said bustle pipe, certain of said links being offset intermediate their ends to accommodate a portion of the bustle pipe when the drill is out of tapping position, a shield carried by said offset links, and lifting means for said drill adapted to travel on said shield during the lifting operation, substantially as described.

6. Blast furnace tapping apparatus, comprising a drill, holding means therefor for holding the drill in tapping-out position, and means for moving the drill to inoperative position, said means being initially operative for releasing said holding means, substantially as described.

7. Blast furnace tapping apparatus, comprising a drill, means for suspending said drill from an overhead support, means for holding said drill in tapping out position, and raising means for said drill operable to initially release said holding means, substantially as described.

8. Blast furnace tapping apparatus, comprising a drill, means for rotating said drill, means for advancing or retracting said drill, a blower pipe, means for advancing or retracting said blower pipe, and suspension means for said apparatus comprising spaced links having pivotal supporting connections at each end thereof, substantially as described.

9. In an apparatus for forming tap-out holes in furnaces, a support, a blower pipe projecting therefrom, a source of fluid under pressure carried by said support, means for swinging said support from operative to inoperative position as required, and means to advance or retract said blower pipe, substantially as described.

10. In an apparatus for tapping blast furnaces, a movable tapping means, holding means movably carried thereby and adapted to hold the same in tapping-out position, and lifting means directly secured to said holding means.

11. In an apparatus for tapping blast furnaces, a movable tapping means, holding means movably carried thereby and adapted to hold the same in tapping-out position, and lifting means directly secured to said holding means, said lifting means being effective for changing the path of travel of said holding means during each lifting operation.

12. In a furnace tapping apparatus, movably mounted tapping mechanism, holding means movably cooperating therewith, lifting means effective for lifting said mechanism only after said holding means has been moved to inoperative position, and an operative connection between said lifting and holding

means effective for first moving the holding means to inoperative position and thereafter lifting said mechanism.

10

In testimony whereof I have hereunto set my hand.

EDGAR E. BROSIUS.
